US0D1049052S

(12) **United States Design Patent** (10) **Patent No.:** **US D1,049,052 S**
(45) **Date of Patent:** **** Oct. 29, 2024**

(54) **ELECTRICAL CONNECTOR**

(71) Applicant: **SAMTEC, INC.**, New Albany, IN (US)

(72) Inventors: **Chadrick Paul Faith**, New Albany, IN (US); **Dale Schmelz**, New Albany, IN (US)

(73) Assignee: **SAMTEC, INC.**, New Albany, IN (US)

(**) Term: **15 Years**

(21) Appl. No.: **29/876,646**

(22) Filed: **May 25, 2023**

Related U.S. Application Data

(63) Continuation of application No. 29/689,980, filed on May 3, 2019, now Pat. No. Des. 1,005,964, which is a continuation of application No. 29/611,521, filed on Jul. 21, 2017, now Pat. No. Des. 964,291.

CLAIM

The ornamental design for an electrical connector as shown and described.

DESCRIPTION

FIG. 1 is a bottom, right, rear perspective view of an electrical connector showing our new design;

FIG. 2 is a top, left, front perspective view thereof;

FIG. 3 is an enlarged top, right, rear perspective view thereof;

FIG. 4 is an enlarged bottom, left, front perspective view thereof;

FIG. 5 is a bottom plan view thereof;

FIG. 6 is a top plan view thereof;

FIG. 7 is an enlarged right side elevation view thereof;

FIG. 8 is an enlarged left side elevation view thereof;

FIG. 9 is a rear elevation view thereof; and,

FIG. 10 is a front elevation view thereof.

The broken lines in the drawings depict portions of the electrical connector that form no part of the claimed design.
